INTERNAL COMBUSTION ENGINE

Franz Lang, Munich, Germany, assignor to Lan-
ova Aktiengesellschaft, Vaduz, LiechtensteinApplication November 13, 1931, Serial No. 574,913
In Germany November 15, 1930

4 Claims. (Cl. 184—18)

A method which has been used for facilitating the starting of an internal combustion engine consists in causing a solvent liquid to trickle down the inner surface of the cylinder, in order to dissolve the film of lubricating oil on that surface and ease the movement of the piston.

In my invention I also use a solvent liquid for the same purpose, but I spray the same into the combustion chamber of the cylinder, at a part near the position of the piston at the end of its outstroke. By injecting the liquid, in the form of spray, I secure better distribution thereof on the cylinder wall. In some cases the liquid, vaporized during the compression stroke, facilitates ignition.

The invention is illustrated in the accompanying drawing, in which Figs. 1, 2 and 3 are partial vertical sections of the cylinder and piston, with the piston in different positions.

20 In the drawing *a* designates the cylinder, *b* the piston, and *c* a nozzle for injecting fuel. In Fig. 1 the piston is shown at the end of its outstroke. A short distance above the face of the piston in this position the cylinder wall has a hole into which a nozzle *d* is fitted. The nozzle has a non-return valve *e* for admitting to the cylinder, from a tube *f*, the liquid for dissolving the lubricating oil. As indicated in Fig. 1 by arrow lines within the cylinder the solvent is sprayed forcibly, and much of the spray strikes the cylinder wall on the opposite side and is flung back, so that it becomes well distributed over the inner surface of the combustion chamber.

35 Fig. 2 shows the piston shortly before completion of its inward stroke, when air for combustion has been compressed together with such part of the solvent liquid as has been vaporized. In Fig. 3 arrow lines indicate the injection of fuel at or near the end of the compression stroke. This is followed by self-ignition.

The device which has been described operates in two steps, the first of which includes the spraying of a combustible liquid oil solvent in the

cylinder of the engine, and the second step includes the injection of the fuel but both steps are carried out at specific positions of the piston. The first liquid which is sprayed into the cylinder is the combustible oil solvent and may be a mixture of paraffin oil and benzol which is vaporized during the compression stroke and facilitates ignition. This liquid also acts to dissolve the oil on the walls of the cylinder to thereby release the piston from a gummed cylinder wall.

What I claim as my invention and desire to secure by Letters Patent of the United States is:—

1. The combination of an internal combustion engine cylinder, a piston working in said cylinder, and a nozzle opening into the combustion chamber of said cylinder near the end position of said piston on its outstroke, said nozzle being adapted for spraying a liquid oil solvent into said cylinder.

2. A device for facilitating the starting of an internal combustion engine having a cylinder and piston therefor, comprising permanent means opening into the cylinder adjacent the end or bottom position of the piston on its outstroke to spray a liquid oil solvent into and on the walls of the cylinder.

3. A device for facilitating the starting of an internal combustion engine having a cylinder and piston therefor, comprising a nozzle opening into the cylinder near the end or bottom position of the piston on its outstroke and having a non-return valve cooperating therewith, said nozzle being adapted to spray an oil solvent against the walls of the cylinder and when the piston reaches the top of its stroke the vaporized oil solvent facilitating ignition.

4. A device for facilitating the starting of an internal combustion engine, comprising permanent means with a check valve adjacent the end or bottom position of the piston of the engine on its outstroke to spray an oil solvent into the combustion chamber of the engine to ease the movement of the piston.
